UNITED STATES PATENT OFFICE

2,556,777

THERMOSTATICALLY CONTROLLED VALVE
FOR SHOWER HEADS

Christian J. Reimuller, Glendora, Calif.

Application February 11, 1949, Serial No. 75,780

5 Claims. (Cl. 236—93)

1

This invention relates to improvements in shower heads, and more specifically to the safety shower head described in my co-pending application Serial #59,393, now abandoned, and to certain mechanical refinements particularly adaptable to said shower head being a first object.

This improvement, in the broad sense, consists in a more adaptive valve and port arrangement desirable in the original structure cited herebefore.

A method has been conceived and revealed in my co-pending application wherein the volumetric flow of fluids from a shower head arrangement as revealed is dependent upon:

(1) the amount of heat available in the fluid contained therein,

(2) its effect upon the thermostatic element enclosed and part of the internal mechanism of the shower head, and,

(3) the size and number of by-pass channels, that are part of the valve face.

The present improvement and invention pertains to an innovation and unique method to reduce the cost of manufacture by making the valve in such manner that said valve serves in its normal function of shutting off the fluid flow, and while being shut will also provide by-pass flow so necessary to the normal operation of such safety shower head described hereinafter.

Other objects enumerated in number in my co-pending application hereinbefore cited are also satisfied by this form of embodiment.

Further objects and advantages of this invention will be apparent from the following description, reference being had to the accompanying drawings, wherein a preferred form of the present invention is clearly shown, and in which like or similar reference characters refer to like or similar parts throughout the several views.

Figure 1 is a transverse cross-sectional view of a shower head equipped with the automatic thermostatic volume reducing means.

Figure 2 is a cross section taken at line 2—2 of Figure 1, showing a mounting journal.

Figure 3 is a plan view of the valve face showing the notches or grooves that allow the valve to leak or pass a proportionately smaller volume of fluid when it is seated on a suitable seat.

Figure 4 is an enlarged cross section showing the manner in which the grooved valve is seated on a valve seat.

Figure 5 is an enlarged perspective view of the valve and a portion of the upper assembly.

Figure 6 is a fragmentary view taken at 6—6

of Figure 1 showing the eccentric used to raise the valve.

Figure 7 is a transverse cross-sectional of the coupling like housing containing the automatic thermostatic volume reducing means, and shows another or alternative form of valve and valve seat.

Figure 8 is a fragmentary, partial, cross-sectional view of the lower portion of Figure 7, and rotated 90 degrees.

Figure 9 is a top plan view of the radially corrugated valve taken at line 9—9 of Figure 7.

Figure 10 is a perspective view of the valve and piston as would be assembled to the thermostatic element.

Now referring to Figure 1, number 1 represents a hydraulic type thermostatic element, held by cotter retainer 2 which resists spring 7. Movable piston 3 carries integrally a valve 4 and a stem 5. Compression spring 6 lifts valve 4 from its seat 8. Said valve is constructed with a serrated face, the serrations being 9. Eccentric 10 on shaft 11 raises the valve 4 when hand set arm 12, held by screw 13 is rotated. Spray plate 14 is screwed into shower body 15, and collar 16 connects the swivel ball 17 to the shower body. Port 18 is for fluid entry.

In Figure 7, number 1a represents the positive displacement hydraulic type thermostat which is held by cotter retainer 2a which resists spring 7a. Movable piston 3a carries a valve 4a and a stem 5a. Compression spring 6a lifts valve 4a off of seat 8a, and should have sufficient force in either construction to do so when operating under normal pressures. Valve 4a is constructed with a radially corrugated face, the serrations being numbered 9a. Raiser cam 20 is mounted on shaft 21 which is in turn drilled internally at 21a to allow for passage of trapped air and fluids from journal 21b. Included is a return spring 22, a reset handle 23 and a packing collar 24 screwed into the body 25 which has two ports; number 18b is for incoming fluids and number 18a is for outgoing fluids, although it is perfectly permissible to reverse the direction of flow and expect good operational results.

Assume that fluid is allowed to enter port 18 of Figure 1. The fluid next enters and passes through the restrictor swivel 17, into the valve body 15 where it surrounds the thermostatic element 1 and then passes through the serrated valve 4 and through the valve seat port 8. Traversing still farther, the fluid passes through the perforated plate 14 where it is converted into a spray.

Should the temperature of the incoming fluid exceed a safe maximum temperature, then the safety feature is brought into operation, thus, the thermostatic element expanding causes valve 4 to be forced shut against seat 8, which upon closing shuts off the primary flow of overheated fluid. In order to bring about the release of said valve 4, the fluid surrounding the thermostatic element 1 must be displaced by cooler fluids resulting from the readjustment of the mixer valves. To accomplish this displacement, a valve with a serrated or "leaky" face is used as shown. (Figure 1, number 4.)

After the overly hot water has been displaced and has left the housing, and when the heat relief is sufficient to cause the thermostatic element to release, return spring 6 assists in raising the valve 4 thereby restoring normal flow to proceed through the device in the normal manner and rate.

Cam 10, rotated by shaft 11 and handle 12 is used to manually restore full flow through the shower head, should a bather wish to take a very hot bath, or to restore full flow without waiting the few moments required for the thermostatic element 1 to react and release valve 4. However, if the valve 4 is manually raised by cam 10, then the override spring 7 must be compressed. The override spring 7 will remain more or less compressed until the thermostatic element cools and retracts the piston 3.

Figure 7 represents a mechanism similar to Figure 1, except the mechanism is shown enclosed in a coupling like body or housing 25 similar to an ordinary pipe coupling. In this form, it can be installed directly in the fluid supply line ahead of the shower head, or in any hot fluid line where it can be used to control fluid flow.

In Figure 7, like numbers represent like parts, the function of which is the same as already described hereinabove. The main reason for Figures 7 to 10 is to show another manner of constructing valve 4, and seat 8 to allow for the necessary by-passing action required in a shower head assembly to which it is attached. Thus, number 1a is the thermostatic unit held by cotter retainer 2a resisting spring 7a, etc.

Valve 4a is radially corrugated and of simple design as to make it a cheap punch press part. It is understood, of course, that the number and depth of the serrations or corrugations will vary the volume of by-pass flow.

Cam 20 held on shaft 21 is another form of reset means, excepting that once the reset button 23 is pressed in, thereby raising the valve 4a by compressing spring 7a, the cam is caught and held by stem 5a seating in groove 26 in which position cam 20 is held until the force delivered through stem 5a has ceased and said stem is retracted a small amount thereby allowing return spring 22 to drive the whole assembly of cam 20 and shaft 21 etc. back to its normal position. Attention is directed to the drilled hole 21a extending through shaft 21 and which is used to exit trapped fluids or air in the cylindrical section forming a bearing 21b. The same effect could be had by drilling a hole through the body 25 from the interior into the journal 21b, or a keyway could be cut in the end of shaft 21 of like length as the drilling shown.

Other minor changes could be arranged, such as using a perforated disc in place of the corrugated one used as the valve 4a; consequently, it is intended that all matter contained in this

description and in the accompanying drawings be considered as illustrative of the theory reduced to actual application and use, and not in a strictly limiting sense.

5. What I claim is:

1. A heat reactive fluid volume controlling means comprising a suitable body housing containing a positive displacement type thermostatic element, said thermostatic element comprising a solid heat reactive core in a rigid case having a cylindrical extension containing a piston, said piston being a stem integral with a corrugated disc valve, the assembly being capable of linear movement within said cylindrical extension, a flat valve seat, an override-holding spring, a valve raising spring and a self-returning latching cam means to engage with said piston, and suitable inlet and outlet ports.

2. A heat reactive fluid volume controlling means comprising a suitable body housing containing a positive displacement type thermostatic element, said thermostatic element operative with a piston and serrated disc valve against a plain valve seat, an override-holding spring, a valve raising spring, suitable inlet and outlet porting means, and a self-returning latching cam means operative with said piston and serrated valve for restoring normal flow.

3. A heat reactive valving means comprising a suitable body housing and spray creating means containing a positive displacement type thermostatic element, said thermostatic element operative with a piston and serrated disc valve against a plain valve seat, an override-holding spring, a valve raising spring, suitable inlet porting means, and a self-returning latching cam means operative with said piston and serrated valve for restoring normal flow.

4. A heat reactive valving means comprising a suitable body housing and spray creating means containing a positive displacement type thermostatic element, said thermostatic element comprising a heat reactive core in a rigid case having a cylindrical extension containing a piston, said piston being a stem integral with a corrugated disc valve, the assembly being capable of linear movement within said cylindrical extension, a flat valve seat, an override-holding spring, a valve raising spring, suitable inlet porting means, and a self-returning latching cam means operative with said piston and corrugated valve for restoring normal flow.

5. A heat reactive valving means comprising a body housing and spray creating means containing a positive displacement type thermostatic element, said thermostatic element operative with a piston and corrugated disc valve against a flat valve seat, an override-holding spring, a valve raising spring, suitable restricted inlet porting means, and a self-returning latching cam means operative with said piston and corrugated valve for restoring normal flow.

CHRISTIAN J. REIMULLER.
